UNITED STATES PATENT OFFICE.

PETER SCHAFFHAUSEN, OF INDIANAPOLIS, INDIANA.

DESIGN FOR A VEHICLE COUPÉ-BODY.

41,223.

Specification for Design.

Patented Mar. 7, 1911.

Application filed December 17, 1910. Serial No. 597,953. Term of patent 14 years.

To all whom it may concern:

Be it known that I, PETER SCHAFFHAUSEN, a citizen of the United States, residing at Indianapolis, in the county of Marion and State of Indiana, have invented a new, original, and ornamental Design for a Vehicle Coupé-Body, of which the following is a specification, reference being had to the accompanying drawings, forming a part hereof.

Figure 1 is a side elevation of a vehicle coupé body showing my new design. Fig. 2 is a rear elevation of the same.

I claim:

The ornamental design for a vehicle coupé body as shown.

In testimony whereof, I hereunto affix my signature in the presence of two witnesses.

PETER SCHAFFHAUSEN.

Witnesses:

W. H. MCKEMER,

JOHN E. SPAAN.
